Attorney.

UNITED STATES PATENT OFFICE.

ANTOINE FRANCE, OF LIEGE, BELGIUM.

MOISTURE-REDUCING PLANT FOR COAL WASHERIES.

Application filed March 8, 1924. Serial No. 697,891.

To all whom it may concern:

Be it known that I, ANTOINE FRANCE, a subject of the King of the Belgians, residing at Liege, Belgium, 17 Quai Saint 5 Leonard, have invented new and useful Improvements in Moisture-Reducing Plants for Coal Washerries, of which the following is a specification.

The present invention relates to improvements in moisture-reducing plant for coal washerries.

The necessity of reducing the moisture contents in washed coal is so apparent that it is unnecessary to dwell further upon it. 15 However, the means employed for this purpose up to the present have been either complex or more or less inefficient. The method most frequently adopted consists in storing coal in an extensive series of storage bins 20 or bunkers, where the drainage takes place, the time required to attain the desired result being, however, considerable. This is due to the fact that the water from the uppermost layers in the bunkers has to percolate 25 through a multiplicity of interstices in order to pass through the stored mass.

The object of the present invention is to remove these drawbacks, and in order that the said invention may be readily understood, 30 stood an embodiment of same is, by way of example, illustrated by the accompanying drawing, which is diagrammatic only, and wherein:

Fig. 1 is a view of the complete plant 35 according to the invention, and

Fig. 2 is a view of a detail on an enlarged scale.

Referring to the said drawing the washed coal is, according to the invention, raised 40 by means of an elevator (a) of the usual type from a hopper (b) onto a scraper-conveyor (c). The coal is delivered onto the stationary upper troughplate (d) of the conveyor and each scraper-plate (e) pushes 45 along in front of it a determined quantity of coal.

The mass reaching the end of the upper troughplate (d) drops through a slot-like opening (f) onto the stationary lower 50 troughplate (g) along which the scraper-plates (e) operate in the opposite direction.

The resistance offered by the coal to its motion forward produces a compression of the mass of particles, which causes an appreciable percentage of moisture to be expelled, and it is to be noted that this wa-

ter squeezed out owing to the above mentioned compression is well separated from the solid mass of particles, and flows freely along in front of the said mass of particles, as shown in Fig. 2. This separation takes place in an extremely short period of time, and consequently the troughplates (d) and (g) along which the material is caused to travel, may be comparatively short.

While travelling along the trough plates (d) and (g) the mass passes over perforated screens (h) arranged at intervals in the said plates.

The perforations of these screens (h) may be of any desired shape, but will preferably have an elongated form. The maximum dimension of these perforations should be slightly less than the maximum size of 75 the particles of coal. Through these perforations the liquid mass drops instantaneously, into collecting hoppers (i) arranged below, carrying with it a few small particles of coal. This mud-like mixture of coal and water runs direct via a pipe or conduit such as (j) Fig. 1 to either the washed coal hopper (b) or to another suitable point of the washery. In the intervals between the successive screens 80 (h) the process of expelling the water by compression due to the masses of coal-particles being pushed forward is continued, and the number of screens (h) is so determined that when the coal has passed 85 over the last of such screens the free water is finally expelled.

It has been found that if the trough-plates be inclined downwardly in the direction of the motion imparted to the coal 90 the release of the water is facilitated.

The coal reaching the end of the lower troughplate (g) after removal of the free water is conveyed towards storage bunkers 100 in any suitable manner.

I claim:

1. In moisture reducing plant for coal-washerries, the combination of a storage hopper for the wet coal; a scraper-conveyor including a plurality of moving scraper-plates substantially at right-angles to the longitudinal axis of said conveyor, a stationary upper troughplate parallel to said axis having a slot-like opening cut therein close to one end and a stationary lower troughplate parallel to said upper trough-plate; a plurality of perforated screens ar-

ranged at intervals in the said trough-
plates; collecting hoppers under said screens
for receiving the muddy water passing
through the latter; and means for removing
5 said muddy water from the base of the last-
named hoppers; substantially as described.

2. In moisture reducing plant for coal-
washeries, the combination of a storage hop-
per for the wet coal; a scraper-conveyor in-
10 cluding a plurality of moving scraper-
plates substantially at right angles to the
longitudinal axis of said conveyor, a sta-
tionary upper troughplate parallel to said
axis having a slot-like opening cut there-
15 in close to one end and a stationary lower
troughplate parallel to said upper conveyor-

plate; a plurality of perforated screens ar-
ranged at intervals in the said troughplates;
collecting hoppers under said screens for
receiving the muddy water passing through 20
the latter; and a conduit for leading the
muddy water discharged at the base of the
last-named hoppers into the aforesaid wet
coal storage hopper.

In testimony whereof I signed hereunto 25
my name in the presence of two subscribing
witnesses.

ANTOINE FRANCE.
